UNITED STATES PATENT OFFICE.

PHILIP PHOEL, OF NEW DORP, NEW YORK.

RING SPRING.

Application filed October 22, 1924. Serial No. 745,051.

To all whom it may concern:

Be it known that I, PHILIP PHOEL, a citizen of Holland, residing at New Dorp, Staten Island, in the county of Richmond and State of New York, have invented certain new and useful Improvements in Ring Springs, of which the following is a specification.

This invention relates to springs or fillers for rings to secure the same safely and reliably to the hand of the wearer.

Among the objects of this invention is to provide a spring or filler for a ring which is particularly adapted to grip the finger of the wearer and to lie concealed within the ring.

Another object of this invention is to provide a spring or filler which can be readily secured to a ring by a strong and reliable connection which is both neat and inconspicuous.

Still another object of this invention is to provide a spring or filler for a ring, said spring being particularly adapted to be neatly and accurately secured within said ring, and in as expedite a manner as possible through manipulation of a tool arranged for that purpose, such tool being preferably of the type disclosed in my co-pending application Serial No. 745,052.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof, reference is had to the accompanying drawings in which like reference characters designate the same parts in the several views, and in which—

Figure 1 is a perspective view of the spring.

Fig. 2 is a longitudinal section of the same.

Fig. 3 is a view showing the spring secured within a ring.

Fig. 4 is an edge view of the same with a part in section on the line 4—4 of Fig. 3.

Referring now more particularly to the drawings, I show the spring or filler as consisting mainly of a clamping or bow-shaped member 10, and having preferably a plurality of side arms or branches 11. This filler which is preferably of arcuate form is readily secured within a conventional ring

12 at the base or under portion thereof and in symmetrical relation therewith. Said filler is made of spring material to resiliently engage or grip the finger of the wearer 60 of the ring. While the filler may be made in different sizes and widths to suit different rings, the flexibility of the ring will afford adjustability of the arms 11 to suit the particular wearer. 65

To secure the maximum degree of flexibility and resiliency, the spring is fastened to the ring at a point remote from the end or ends thereof, and preferably at the center 70 13 thereof as shown. The arms 11 are thus 75 in effect attached resiliently at 13 and will be flexed away from each other when the wearer inserts his finger into the ring, the result being not only to grip said finger at two points thereof thus minimizing the 75 tendency for the usual accidental turning of the ring about the finger but also to properly center the finger within the ring. As will be observed, the arms 11 are spaced 80 inwardly from the sides of the ring so as to permit of outward movement thereof both for the purpose of providing for the initial adjustment of the spring and to secure the necessary give for the purpose of obtaining 85 a resilient gripping effect. The spring is rounded at the main points of contact thereof with the wearer to permit of an easy insertion or removal of the finger from the ring, and with as little strain as possible upon the connection referred to whereby the 90 spring is secured to the ring. More particularly, the ends of the spring are rounded or cupped inwardly at 14, providing a convex surface 15 to afford a comfortable and easy sliding contact with the finger of the 95 wearer as well as an effective gripping thereof. The rounded or cupped portions of the spring may be made somewhat wider for this purpose than the main portion of the spring which is preferably of less width 100 than the ring wherein it is used so as to facilitate concealment thereof within the ring when worn in the usual manner. The spring is thus positioned in the ring within the planes bounding the sides thereof, and secured in sufficient rigidity thereto to preclude the possibility of movement of the 105 spring beyond said planes while in use.

The spring is fastened to the ring in a rigid manner and in such way as is consistent with the objects of this invention. Preferably it is soldered thereto at the center 110

portion 13 of the spring as already indicated. To provide space for the solder so that the connection may be as neat and inconspicuous as possible, a dent or groove 16 is formed in the bottom of the spring. A lip or lug 17 is likewise formed at the central portion of the spring and preferably as a result of striking said groove, thus providing means for holding the central portion 10 of the spring against movement while inserting the spring into the ring, as well as additional means for gripping the finger of the wearer. The spacing of the arms 11 from the sides of the ring provides for the ready gripping thereof by said tool, and facilitates the manipulation and adjustment thereof within the ring for the purposes of securing alinement and proper fastening connection. By means of the tool aforesaid, the spring is first held in automatic adjustment within the ring, and the solder is applied while so held to fasten the same.

I claim:

- 25 1. The herein described filler for a ring arranged to be secured at a point within the ring, said filler being of uniformly constant width at the point of attachment and adapted to lie wholly within the planes bounding the sides of said ring, said filler being of substantially flat cross section at the point of attachment so as to lie snugly against the inner surface of the ring but having a cup pressed inwardly from the surface of contact between the filler and the

ring at said point of attachment so as to 35 permit a quantity of solder to be contained within said cup for securing the filler snugly to the ring.

2. The herein described filler for a ring arranged to be secured at a point within the 40 ring, said filler having a portion arranged to closely contact the inner surface of the ring, said portion having a cup formed inwardly toward the center of the ring, the opening of said cup lying in the surface of 45 contact between the filler and the ring so that said ring acts as a closure for said cup when the filler is arranged therein, said cup being adapted to contain solder to secure the filler to the ring and to contain said 50 solder from spreading when the filler is attached to the ring.

3. The combination with a ring, of a filler arranged to be secured therein at a portion thereof, said portion having a surface 55 formed to lie in close contiguity to the inner surface of said ring, an inwardly extending cup being formed in said portion having its opening in the surface of contact between the filler and the ring, and solder within 60 said cup to secure the filler to the ring, said solder being confined within said cup by the ring acting as a closure therefor at said surface of contact to prevent spreading of the solder and injury to the ring while the 65 filler is being attached.

In testimony whereof I affix my signature.

PHILIP PHOEL.
